UNITED STATES PATENT OFFICE.

HARVEY D. DIBBLE, OF ROCHFORD, DAKOTA TERRITORY.

SYSTEM OF ELECTRIC PROPULSION.

SPECIFICATION forming part of Letters Patent No. 406,391, dated July 2, 1889.

Application filed February 2, 1889. Serial No. 298,449. (No model.)

To all whom it may concern.

Be it known that I, HARVEY D. DIBBLE, of Rockford, in the county of Pennington and Territory of Dakota, have invented a new and 5 Improved System of Electric Propulsion for Common Roads, of which the following is a specification, reference being had to the annexed drawings, forming a part thereof, in which—

10 Figure 1 is a side sectional elevation of an electrically-propelled wagon, showing the electrical conductors and the devices for transmitting the current from the conductors to the motor of the wagon. Fig. 2 is a sectional 15 elevation looking toward the front of the wagon, the steering-wheel being removed. Fig. 3 is a plan view. Fig. 4 is a plan view of the steering-gear; and Fig. 5 is a side elevation, partly in section, of the trolley which runs 20 upon the wire and takes off the current.

Similar letters of reference indicate corresponding parts in all the views.

The object of my invention is to provide a system of electrical propulsion for common 25 roads, by means of which traffic may be carried on without the necessity of employing a railway-track, and to so arrange the steering-gear that the wagon will automatically run parallel with the line of the conductors.

30 My invention consists in the construction and arrangement of parts, as will be herein-after fully described and claimed.

The wagon-body A, to which my improvement is applied, is supported upon the axle 35 B, which carries the drive-wheels C, and also upon a caster-wheel D, provided with a fork a, journaled in the forward end of an extension E of the frame of the body A. Upon the axle B is mounted the spur-wheel F, which is 40 engaged by a pinion G upon the armature-shaft b of the motor H, the said motor being secured to the main frame of the body A. The shank c of the fork a extends upwardly through a sleeve d, placed loosely on the said 45 shank, and upon the upper end of the shank c is mounted a steering-lever e, provided with a latch f, which engages a notched flange g upon the upper end of the sleeve d. Between the lower end of the sleeve d and the extension E a sprocket-wheel h is secured to the 50 sleeve d.

In the extension E, in front of the wagon-box I, is journaled the shaft i of the fork J, and upon the said shaft is secured a sprocket-wheel j, which receives an endless chain K, 55 passing around the sprocket-wheel h upon the shank c.

Above the road-bed L are suspended electrical conductors l l' l'' l'', by means of L-shaped hooks m, suspended from the bracket 60 M, the said bracket being supported by a pole N. These conductors are preferably located at a central point above the road-bed, and are supported by as many poles N and brackets M as are necessary to give the conductors the 65 required rigidity.

Each wagon is provided with a trolley, O, which rides upon a pair of the conductors. In the present case the trolley is shown running upon the conductors l' l''. The frame n of the 70 trolley is provided with the cross-arms o, which are each furnished with two pairs of vertical studs p, upon which are placed rollers q, the rollers of each pair being adapted to roll upon opposite sides of the conductors 75 l' l'', and the frame is also provided with horizontal studs r r', projecting from opposite sides parallel with the arms o. The rollers q form vertical guides for the trolley and prevent it from leaving the conductors. Upon 80 the studs r r' are placed rollers s s', the rollers s being adapted to roll upon the conductor l'', and the rollers s' being arranged to roll upon the conductor l''. The studs r r' are insulated from each other and from the frame 85 n, and the conductors t t', which lead to the brushes of the motor H, communicate with the conductors l'' l'' through the said rollers s s'.

In the center of the trolley O there is a chamber u, provided with a cap v. The shank w of the fork P extends through the frame of the trolley through the chamber u and through the cap v, and is provided with a nut a', by which it is held in place. In the chamber u, and surrounding the shank w, is placed a spiral-spring b', one end of which is attached to the shank w, the other being inserted in the cap v. The office of this spring is to hold the fork P in its normal position while allowing it to yield a certain amount in either direction. 95 100

In the fork P is pivoted a knuckle c', pro-

vided with a transverse aperture, which receives the right-angled end d' of the inclined steering-rod Q . The opposite end of the rod Q is pivoted in the fork J .

- 5 The driver's seat is supported by a spring f' , secured to the extension E , between the sprocket-wheels h, j . The driver of the wagon is able to guide it, when desired, by turning the caster-wheel D in one direction or the other. By virtue of the connection between the shank c of the caster-wheel and the shaft i of the fork J , the said wheel is turned so as to cause the wagon to move forward parallel with the conductors $l^2 l^3$, maintaining its parallelism with the said conductors. Ordinarily the wagon will run in a line parallel with the conductors, being guided by the movement of the steering-wheel caused by the connection therewith of the shaft i , which is turned 15 by the steering-rod Q , as the trolley follows the deviations from a straight line of the conductors, the driver not being required to use the steering-lever e , except when it is needful to turn aside from any cause, and when so turned aside the wagon can be made to run in a new line by placing the lever in one of the side notches of the flange g .

The yielding nature of the connection between the wagon and the trolley permits of 30 sufficient movement of the wagon to allow one wagon to turn out for another upon the road, or to run at one side of the conductors, as indicated in Fig. 2. In this case the latch f is placed in one of the notches in the flange g of the sleeve d , thus allowing the rod Q to take an oblique position, while the caster-wheel remains parallel with the course of the wagon.

It is obvious that with a wagon having an 40 electric motor of sufficient capacity the wagon itself may be made to carry a load as well as to propel a train connected with it.

Having thus described my invention, I claim as new and desire to secure by Letters Patent—

45 1. In a system of electric propulsion for common roads, the trolley having opposite front and rear pairs of vertical rollers, and horizontal rollers insulated from each other and from the frame or body, substantially as set forth.

50 2. In a system of electric propulsion for common roads, the trolley consisting in a frame, opposite depending front and rear pairs of vertical rollers, opposite front and rear 55 horizontal rollers insulated from each other and the frame, and a central vertical shank journaled in the frame and having a fork on its lower end, substantially as set forth.

3. In a system of electric propulsion for 60 common roads, the trolley consisting in a frame having a central vertical chamber apertured in its bottom and having an apertured cap plate or cover, a shank extending through said apertures and having a fork 65 at its lower end, a spring surrounding the shank within the chamber and connected at

its end with the shank and cap plate, respectively, opposite front and rear pairs of vertical rollers depending from the frame, and opposite front and rear horizontal rollers insulated from each other and the frame, substantially as set forth. 70

4. The combination, with the overhead conductors and the trolley thereon, having a vertical shank journaled thereon, of a road-wagon 75 having a motor connected with the trolley, a vertical shaft journaled on the wagon, and a rod pivoted or hinged at its ends to said shank and shaft, substantially as set forth.

5. In a system of electric propulsion for 80 common roads, the wagon provided with drive-wheels and a steering-wheel having a vertical axis or shaft provided with a locking mechanism and a sprocket-wheel, a vertical shaft between the drive and steering wheels, 85 a sprocket-wheel thereon, a chain connecting said sprocket-wheels, a rod pivotally connected to the upper end of said second vertical shaft, and an electric motor, the shaft of which is geared to the axle of the drive-wheels, 90 substantially as set forth.

6. In a system of electric propulsion for common roads, the combination of a trolley provided with the conductors $t t'$, the vertical rollers q , and horizontal rollers $s s'$, the wagon 95 provided with a body A , the axle B , drive-wheels C , caster-wheel D , motor H , and means for connecting the motor and the trolley, substantially as specified.

7. In a system of electric propulsion for 100 common roads, the combination of the suspended conductors $l^2 l^3$, the trolley provided with the frame n and chamber u , and having arms o , the studs p , and insulated studs $r r'$, the rollers q , journaled on the studs p , the 105 rollers $s s'$, journaled on the studs $r r'$ and adapted to roll on the conductors, the fork P , furnished with the shank w , journaled in the frame n , and the spring b' , connecting the frame n and the shank w , substantially as 110 specified.

8. In a system of electric propulsion for common roads, the combination of the suspended conductors $l^2 l^3$, the trolley provided with the frame n and chamber u , and having 115 arms o , the studs p , and insulated studs $r r'$, the rollers q , journaled on the studs p , the rollers $s s'$, journaled on studs $r r'$ and adapted to roll on the conductors, the fork P , furnished with the shank w , journaled in the 120 frame n , the spring b' , connecting the frame n and the shank w , the knuckle c' , the rod Q , provided with the right-angled end d' , the shaft i , carrying the slotted fork J , the sprocket-wheel j , attached to the said shaft, 125 the caster-wheel D , the shank c , the sprocket-wheel h , and the endless chain K , connecting the sprocket-wheels h, j , substantially as specified.

9. In a system of electrical propulsion, the 130 combination, with overhead electrical conductors, a trolley adapted to run thereon, a

wagon provided with an electric motor, and connections between said motor and conductors, of a caster-wheel on the wagon, a sleeve on the shank of said caster-wheel carrying a 5 sprocket-wheel, a vertical shaft journaled on the wagon provided with a sprocket-wheel, a belt connecting said sprocket-wheels, a steering-rod swiveled to the trolley and to the said vertical shaft, and a steering-lever on the shank of the caster-wheel, all arranged for operation as and for the purposes set forth.
